THROW-AWAY SHIELD AND METHOD OF
FABRICATING SAME

Herman J. Ermisch, Terre Haute, Ind.

Application August 4, 1939, Serial No. 288,300

11 Claims. (Cl. 2—53)

This invention relates to a "throw-away" shield and its method of manufacture.

The chief object of this invention is to produce a shield of the aforesaid character whereby the same may be readily attached to a garment for protecting same from perspiration and the like and which is anchored to the garment without garment penetration and which exposes no metal to the skin of the garment wearer, thereby preventing skin abrasions, discolorations or creation of allergic eruptions thereon.

One of the main difficulties, annoyances, and elements of cost in the dry cleaning industry is the removal and replacement of rubber dress shields prior and subsequent to frock cleaning for example. If such are not removed, the cleaning operation vulcanizes them, that is, destroys the elasticity, and the frock owner demands new shields, as well as the removal of the deteriorated shields.

Light weight shields, other than of rubber, have been fabricated but require either garment penetration or skin exposure if anchored other than by sewing (tacking) or must be used as a loose insert.

The present invention, therefore, permits shields to be readily anchored or detached without the aforesaid objections and all without the tacking or sewing of the shield to the garment.

The chief feature of the invention consists in forming a shield from a material suitable for reasonable use and provided with garment anchoring means of garment gripping, as distinguished from garment penetrating character and which means is not exposed to the wearer and may also be incorporated so as not to be directly exposed to the garment.

Other objects and features of the invention will be set forth more fully hereinafter.

The method invention whereby the article invention is produced essentially consists of forming the shield material with the anchor means included therein and thus secured thereto, and if desired, covered by a portion of such material.

Herein this material is of multiply character including a fibrous interior such as sheeted absorbent cotton about $\frac{1}{16}$ " to $\frac{1}{8}$ " in thickness between two layers of retaining material such as a fine grade of cheese cloth or the like. Embedded in the fibrous interior upon the inner face of the shield and retained upon the shield by the adjacent retainer layer are the anchor means. These may be further masked as hereinafter set forth, if desired.

The edges of the shield forming blank may be hemmed by overcast sewing or the like, but preferably is of pressure interlocked character as hereinafter set forth more fully herein.

5 The resulting shield is formed from a single blank and is of conventional shield outline, size and shape differing only from present non-rubber shields as described hereinafter.

The full nature of the invention will be understood from the accompanying drawing and the following description and claims:

In the drawing, Fig. 1 is a plan view of the shield prior to its last operation. Fig. 2 is a perspective view of such a shield. Fig. 3 is an enlarged sectional view through the shield material with the anchors included therein prior to formation into anchor form. Fig. 4 is an enlarged perspective view of the anchor member. Fig. 5 is an elevational diagrammatic view of anchor member blank formation. Fig. 6 is a similar view of apparatus suitable for the final or semi-final step in the shield formation and with the assembled shield forming materials properly associated therewith prior to formation as illustrated in Fig. 2 wherein the clip is then shaped as illustrated in Fig. 4.

In Fig. 3 of the drawing, 10 indicates a layer of sheeted cotton of absorbent character about $\frac{1}{8}$ " in thickness; 11 indicates a lower layer of cheese cloth or the like; 12 indicates an upper layer of the same material or one having moisture resistance or being water repellent. If the latter be used the life of the resulting shield is correspondingly increased.

35 Whether one or the other material be used the present invention is not confined thereto. In Fig. 1 of the drawing same is illustrated in plan but at a later stage in the production.

Prior to the application of layer 12 to layer 10 metal strips 13 are placed upon the batting and the layer 12 covers the same and strips and secures the two together. The resulting strip embedded material is then cut to the outline as shown in Fig. 1 so as to form the shield shown in Fig. 2.

The registering exterior edges 14 may be sewed together or the like or may be pressure locked together as at 15. The latter action may occur simultaneously with the cutting of the blank. 50 The interior outline 16 is preferably formed when the blank is formed. The two resulting lunar or crescent shaped portions 17 are thus connected as at 18. If desired, the outline 16 may be pressure locked together as indicated at 19 simultaneous with outline formation or omitted. If

incorporated at this stage of fabrication, when the blank is folded medianly upon itself to form the article as shown in Fig. 2, these compressed edges may be stitched together. If the outline edge 16 be not thus initially compressed when the lunar portions are superposed these mating edges 16 may be pressure locked together as previously described and/or may be sewed together.

Reference will now be had to Fig. 4. The clip illustrated therein is about $\frac{1}{8}$ " wide and about $\frac{3}{8}$ " to $\frac{1}{4}$ " in length with a central bowed portion 20, two clamping lips 21 defined by outwardly directed tips 22 to lock into the body of the shield and to facilitate attachment and removal of the clip to and from the garment. The bowed portion 20 is provided to accommodate the garment seams, that is, where the sleeve and arm hole portions of the garment are joined together.

Fig. 5 illustrates a dual type mechanism for forming the clip forming blank as indicated at 13. The metal stock 30 at station A is formed V-shaped in outline, as shown, and at station B is severed therefrom forming the strip 13 with tips 13a which constitute tips 22 in the final clip.

After the clip blank has been formed as described, it is operated upon at station C, see Fig. 6, which curves the body portion of the strip 13 into the bowed portion 20 of the clip and such bowing positions lips 20 substantially together so that, since stock 30 is of spring steel or the like, the lips tend to resist undue separation or opening.

The blank, when finished in the manner described, thus provides at each end or tip of the shield, and at the junction between the lunar portions thereof, see Figs. 1 and 2, an anchoring clip for garment engagement.

If desired, prior to the final formation of the strip into clip form there may be applied thereto, as indicated at 40, a larger and covering strip of adhesive type tape or cellulose. This addition, naturally, protects the garment from direct metal contact and serves as an additional anchorage for securing the clip to the shield blank, and reinforces the lunar connections.

As shown in Fig. 1, the strip 13 is applied to the shield body stock, and if desired, covered with tape 40, all as shown in Fig. 3. In either event the operation shown in Fig. 6 as well as the operation necessary to form the blank in Fig. 1 are then performed, the result being the shield shown in Fig. 2.

Fig. 6 also illustrates the preferred final or semi-final step of the process. The stock has been built up as shown in Fig. 3 with the clip blank shown in Fig. 5 embedded therein, see also Fig. 1. When the punch descends or the female die and support elevates, or both occur, the clip blank is changed in shape to that illustrated in Fig. 4 but same is concealed within the shield, see Fig. 2.

While the invention has been illustrated and described in great detail in the foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a shield having two wings each of crescent outline and joined together upon an interior edge, the combination of a pair of non-

penetrating and garment seam clamping anchorages one at each tip and each secured to both wings adjacent the connection therebetween and positioned inwardly of the folded wings, each anchorage including a resilient clamping clip having opposed lips fully enclosed within the wings, a central seam receiving bowed portion for wing connection and oppositely directed tips for facilitation of shield mounting, and means covering each anchorage and facilitating the connection thereof to the wings and reenforcing the wing to wing connection.

2. In a shield having two wings each of crescent outline and joined together upon an interior edge, the combination of a pair of non-penetrating and garment seam clamping anchorages one at each tip and each secured to both wings adjacent the connection therebetween and positioned inwardly of the folded wings, each anchorage including a resilient clamping clip having opposed lips, a central seam receiving bowed portion for wing connection and oppositely directed tips for facilitation of shield mounting, the shield forming material including a fibrous interior and adjacent facings therefor, said interior and adjacent facings being secured together at their registering peripheries, and means covering each anchorage and facilitating the connection thereof to the wings and reenforcing the wing to wing connection.

3. In a shield having two wings each of crescent outline and joined together upon an interior edge, the combination of a pair of non-penetrating and garment seam clamping anchorages one at each tip and each secured to both wings adjacent the connection therebetween and positioned inwardly of the folded wings, each anchorage including a resilient clamping clip having opposed lips, a central seam receiving bowed portion for wing connection and oppositely directed tips for facilitation of shield mounting, the shield forming material including a fibrous interior of felted cotton fibre or padding and adjacent facings of cheese cloth and the like therefor, said interior and adjacent facings being secured together at their registering peripheries, and means covering each anchorage and facilitating the connection thereof to the wings and reenforcing the wing to wing connection.

4. The method of fabricating a throw-away shield including forming a blank providing two crescent shaped wing portions, securing thereto at the adjacent tip forming portions a flexible clip forming strip, and then forming the strips into wing-concealed and anchored clamping clips when the wing portions are arranged in shield formation.

5. A method as defined by claim 4, characterized by the formation of the blank from laminated material and the securing of the remote edges of the laminations of each of the wing portions together, and securing together all the edges of the laminated material at the adjacent edges of the wing portions.

6. A method as defined by claim 4, characterized by the formation of the blank from laminated material and the securing of the remote edges of the laminations of each of the wing portions together, and securing together all the edges of the laminated material at the adjacent edges of the wing portions, the securing of the remote edges being of a pressure connection character.

7. A method as defined by claim 4, characterized by the formation of the blank from lam-

inated material and the securing of the remote edges of the laminations of each of the wing portions together, and securing together all the edges of the laminated material together at the adjacent edges of the wing portions, the securing of the adjacent edges of and the wing portions together being of pressure connection character.

8. A method as defined by claim 4, characterized by the formation of the blank from laminated material and the securing of the remote edges of the laminations of each of the wing portions together, and securing together all the edges of the laminated material at the adjacent edges of the wing portions, the securing of the remote edges being of a pressure connection character, the securing of the adjacent edges of and the wing portions together being of pressure connection character.

9. A method as defined by claim 4, characterized by the formation of the blank from laminated material and the securing of the remote edges of the laminations of each of the wing portions together, and securing together all the edges of the laminated material at the adjacent edges of the wing portions, the securing of the remote edges being of a pressure connection character. the blank formation and pressure connection being simultaneously effected.

10. A method as defined by claim 4, characterized by the formation of the blank from laminated material and the securing of the remote edges of the laminations of each of the wing portions together, and securing together all the edges of the laminated material together at the adjacent edges of the wing portions, the securing of the adjacent edges of and the wing portions together being of pressure connection character, the blank formation and pressure connection being simultaneously effected.

11. A method as defined by claim 4, characterized by the formation of the blank from laminated material and the securing of the remote edges of the laminations of each of the wing portions together, and securing together all the edges of the laminated material at the adjacent edges of the wing portions, the securing of the remote edges being of a pressure connection character, the securing of the adjacent edges of and the wing portions together being of pressure connection character, the blank formation and pressure connection of the remote edges occurring simultaneously and prior to clip formation, and the latter occurring prior to adjacent edge wing connection.
